UNITED STATES PATENT OFFICE

2,356,239

STERILIZER

Vincent Giuliana, Springfield, Mass.

Application April 11, 1944, Serial No. 530,446

4 Claims. (Cl. 21—91)

This invention relates to improvements in sterilizing apparatus.

The principal objects of the invention are directed to improvements in sterilizers particularly adapted for sterilizing barbers' implements and the like.

According to the novel features of the invention, a unitary structure is provided which includes a base and walls arranged in a novel manner to form separate compartments having communicating means and guiding means for implements.

Various novel objects and advantages of the invention will be hereinafter more fully referred to in connection with the following description of the invention in the form at present preferred.

In the drawing:

Fig. 1 is a plan view of a sterilizer embodying the novel features of the invention;

Fig. 2 is a front elevational view of the sterilizer shown in Fig. 1;

Fig. 3 is a side elevational view of the sterilizer shown in Figs. 1 and 2; and

Figs. 4 and 5 are sectional elevational views on the lines 4—4 and 5—5 of Fig. 1 respectively.

Referring now to the drawing in detail, the invention will be fully described.

A base 2 is provided for supporting the structure. A rear wall 4 extends vertically upwardly from the base. One end wall 6 extends upwardly from the base 2 as does an intermediate wall 8. To these walls 6 and 8 a front wall 10 is connected. Said wall 10 inclines inwardly and downwardly from its upper end so as to form with the walls 4, 6 and 8 and the base 2 a wedge shaped compartment open at its upper side. This may be called an auxiliary compartment.

A partition 12 extends inwardly from the wall 4 whereby separate compartments 14 are provided in the auxiliary compartment.

Walls 18 extend inwardly of the rear wall within the auxiliary compartment to which is secured a front wall 20. These walls are arranged to cooperate with the rear wall 4 to form a receptacle 22 that is wedge shaped or gradually narrows downwardly.

An end wall 24 extends upwardly from the base 2 and forwardly from the rear wall 4 and a front wall 26 extends from the base to connect walls 8 and 24. These walls are arranged to form a wedge shaped main compartment which is open at its upper side.

A guide member is provided which has a rear wall 28, a front wall 30 and end walls 32, that are arranged to lie against the walls 4, 8, 24 and 55

26. A flange 34 projects outwardly from the upper ends of the walls of the guide member for resting on the upper edges of the walls of the main compartment.

The guide member formed by the walls described is adapted to be inserted in the main compartment and to be withdrawn therefrom.

Inwardly extending partitions 35 are provided on the wall 30 and are spaced apart to provide pockets such as 36.

A longitudinal wall 38 extends between the walls 32 and partitions 40 extend between walls 28 and 38 to form guideways 42.

A well 44 is provided in the base 2 and it has an inclined bottom 46, as shown. Ears 48 extend upwardly at the sides of the well.

Sterilizing material in the form of a liquid may be placed in the main and auxiliary compartments as well as in the well. The wall 20 of the compartment 22 is provided with an opening 50. The wall 8 between the main and auxiliary compartments is provided with an opening 52 so that the compartments are in communication whereby the level of liquid will be the same in all of the compartments.

The sterilizer is particularly adapted for barbers' implements and to that end tweezers may be inserted in the compartment 22 while combs may be placed in the compartments 14 of the auxiliary compartment.

Razors may be placed between the partitions 35 and shears in the guideways 42.

The guide member in the main compartment may be withdrawn therefrom and the implements therein may be arranged so as to be withdrawn or inserted with the guide member.

Clippers may have their working head disposed in the well, the inclined surface 46 serving to support the head of said clippers.

Preferably the sterilizer will be made from some transparent material such as glass and the guide member may be also made from glass or a suitable plastic material. By being transparent the implements in the compartments will be visible.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended

claims are therefore intended to be embraced therein.

What it is desired to claim and secure by Letters Patent of the United States is:

1. A sterilizer of the class described comprising in combination, a base, rear, front, end and intermediate walls extending upwardly from the base forming therewith an auxiliary and a main compartment open at upper sides separated by said intermediate wall, a guide member having rear, front and end walls insertable in the main compartment, walls associated with the said rear wall in the auxiliary compartment forming therewith a wedge shaped compartment, one of said walls and said intermediate wall provided with an opening whereby said wedge shaped compartment, auxiliary compartment and main compartment are in communication for the passage of liquid therebetween, and partitions associated with the walls of the guide member forming guideways for implements.

2. A sterilizer of the class described comprising in combination, a base, rear, front, end and intermediate walls extending upwardly from the base forming therewith an auxiliary and a main compartment open at upper sides separated by said intermediate wall, a guide member having rear, front and end walls insertable in the main compartment, walls associated with the said rear wall in the auxiliary compartment forming therewith a wedge shaped compartment, one of said walls and said intermediate wall provided with an opening whereby said wedge shaped compartment, auxiliary compartment and main compartment are in communication for the passage of liquid therebetween, and partitions associated with the walls of the guide member forming guideways for implements, said front walls inclined inwardly and downwardly relative to the rear wall whereby the main and auxiliary compartments are wedge shaped.

3. A sterilizer of the class described comprising

in combination, a base, rear, front, end and intermediate walls extending upwardly from the base forming therewith an auxiliary and a main compartment open at upper sides separated by said intermediate wall, a guide member having rear, front and end walls insertable in the main compartment, walls associated with the said rear wall in the auxiliary compartment forming therewith a wedge shaped compartment, one of said walls

5 and said intermediate wall provided with an opening whereby said wedge shaped compartment, auxiliary compartment and main compartment are in communication for the passage of liquid therebetween, and partitions associated with the walls of the guide member forming guideways for implements, said front walls inclined inwardly and downwardly relative to the rear wall whereby the main and auxiliary compartments are wedge shaped, and said base provided with a well separate from said compartments.

4. A sterilizer of the class described comprising in combination, a base, rear, front, end and intermediate walls extending upwardly from the base forming therewith separate auxiliary and main compartments open at upper sides and separated by said intermediate wall, a separate guide member having rear, front and end walls, walls associated with the said rear wall in the auxiliary compartment forming therewith a wedge shaped compartment open at its upper side, one of said walls and said intermediate wall provided with an opening whereby said wedge shaped compartment, auxiliary compartment and main compartment are in communication for the passage of liquid therebetween, and partitions associated with the walls of the guide member forming guideways for implements, said guide member adapted for insertion in and withdrawal from 40 said main compartment.

VINCENT GIULIANA.
